UNITED STATES PATENT OFFICE.

CHARLES H. J. DILG, OF NEW YORK, N. Y.

DRILLING AND TAPPING DEVICE.

1,071,216.

Specification of Letters Patent. Patented Aug. 26, 1913.

Application filed April 30, 1910. Serial No. 558,586.

To all whom it may concern:

Be it known that I, CHARLES H. J. DILG, a citizen of the United States of America, and a resident of New York, in the county 5 and State of New York, have invented a certain new and useful Drilling and Tapping Device; and I hereby set forth such a full, clear, and exact description of the same as will enable the invention to be fully understood by those skilled in the art.

This invention relates to appliances which may be used for boring holes in metal, stone or other hard substances, or for cutting threads of internal screws or nuts, and the 15 like; and which are known generally as drilling and tapping devices.

My invention consists of certain novel features of construction and combination and arrangement of parts, forming in operation a simple and efficient organization.

In order to enable the invention to be fully understood, I shall proceed to explain the same by reference to the drawings, illustrative of embodiments of the invention, 25 which accompany and form a part of this specification, and in which—

Figure 1 is a longitudinal sectional view of an appliance constructed according to my invention; Fig. 2 is a view in section taken 30 on the line 2, 2, Fig. 1; Fig. 3, is a longitudinal sectional view of another embodiment of my invention; Fig. 3^a is a detail sectional view taken on the line 3, 3, Fig. 3; Fig. 4 is a longitudinal sectional view of a drilling 35 and tapping device embodying my invention, the casing of which is formed with a yoke and set collar; Fig. 5 is a plan view of another embodiment of my invention. Figs. 6 and 7 are sectional longitudinal views on a 40 reduced scale of other embodiments of my invention, and Figs. 8 and 8^a are views in detail of my friction driving clutch for the flexible shaft.

Like letters of reference indicate like parts 45 in all the views.

This invention is peculiarly adapted for the purpose of drilling and tapping holes in work which it would be inconvenient and expensive to handle in taking it to and from 50 drill presses and tapping machines. Being of small dimensions and also of a portable nature, it can also be advantageously used in places where a machine of large size could not be conveniently employed.

55 The illustrated embodiments of my invention consist essentially of a driving power

actuated member, and a driven member provided with a suitable appliance, as a chuck, to hold the cutting tool, or the tap, the latter member being adapted to be connected with the driving member so as to be operated in a forward or reverse direction, by the following means:—Two oppositely disposed gear wheels are respectively formed with clutch members, intermediate of which is located a third reciprocatory clutch member, secured to or forming a part of the driven member, carrying the chuck, which is thereby adapted to be placed in operative relation with one or the other of said gears, which are actuated by the driving member. The oppositely disposed gear wheels carrying the clutch members *f* are respectively denoted in Figs. 3, 4 and 5 by the reference characters *F*, *F'*, which are inclosed in the casing *A*¹⁰ and placed in mesh with an intermediate gear *G'*, and sometimes with two oppositely disposed gear wheels *G*, *G'*, working on shafts *g*, as shown in Figs. 3 and 4, whereby the gear wheels *F* and *F'* will be caused to rotate in opposite directions. The intermediate clutch member *C*² is attached to the driven shaft or tool spindle *C*¹⁰ carrying the chuck *C'*.

By means of the above structure, a reversing mechanism is afforded, so that when used for the purpose of tapping, the tap may be run into the hole and out of it, without changing the rotation of the driving shaft. For example, if the tap is pressed against an object, the shaft and clutch are lifted or moved rearward, which causes the intermediate clutch member to come into contact with the clutch member of the rear gear wheel, thus moving the driven member and chuck in a given direction, and when the tool is withdrawn, the friction, or gravity, causes the clutch of the shaft carrying the chuck to come into contact with the forward gear clutch, and the driven shaft is consequently rotated in a contrary direction—the clutches being thus opened or closed, in operation, by pressing the tool against an object or by pulling the same backward. When used as a drilling device, the intermediate clutch member, which otherwise remains movable longitudinally for the purpose of reversing the rotation of the driven shaft, may be locked by means of a set collar *P*, or by any other suitable means, 105 so that the driven member will revolve in one direction only, whether a right hand or

a left hand rotation. This is of particular advantage where the driving means rotates in a left hand direction, as in the case of an electric motor, where a right hand drill 5 may be used by setting the collar so that the reversing gears will be constantly kept in mesh. For the purpose of protecting and adjusting the said set collar, the casing of the appliance is usually formed with a 10 yoke O.

10 I ordinarily make one of the gear wheels, as F, larger in diameter than the other one, as F', whereby, if the intermediate clutch member C² is locked in mesh with one of 15 the gear wheels, as F', it will run at a different rate of speed than when in mesh with the other gear wheel, as F, and consequently, large or small drills may be run at different speeds; or by inserting gear wheels of different ratios, the device may be made capable of imparting any number of speeds 20 to drills or taps of different sizes, or when used for different materials.

25 My appliance is usually supplied with a plurality of handles, as A⁴, of which, one may be used for holding it, and the other for purposes of guiding and steadyng the same, and one or both of these handles may be removable, so that it will be adaptable to 30 two positions, either at the side of the device, or at the back of it, and being hollow, it may be slipped over a flexible shaft B, or over a tapered spindle B¹⁰ of the tool, which is adapted to fit into a drill press, for instance, or the said handle may be secured directly onto the frame of the machine, as by being engaged with the thread a²⁰ of the same.

35 Sometimes I dispense with the use of two intermediate gear wheels G, G' and only employ one of them, as shown in Fig. 5, but I prefer to use both wheels, as when both of the same are used, there is a leverage exerted on both sides of the gear F', whereby 40 they serve the purpose of taking up or avoiding the strain or side thrust from the gear wheels against the bearings, when only one is used.

45 When my appliance is used in connection with a drill press, the tapered spindle B¹⁰ is inserted into a socket of the machine. If, however, it is operated by means of a flexible shaft B, the latter is connected to the shaft B' as hereinafter described, and the 50 handle may be placed over the tapered spindle, and the side handle may be removed, or both handles may be employed, as illustrated in Fig. 5.

55 In Figs. 1 and 2, an arrangement of the parts is shown, where the gear wheels are 60 arranged in parallel, the driving member B' carrying a gear b which meshes with the gear d, mounted on the auxiliary shaft D, at the other end of which is located a gear 65 d' which meshes with a gear e of the spindle

E, which, in turn, meshes with the gear C³, the gears b and C³ forming clutch members, the same being alternately engaged with the intermediate clutch member C², mounted on the shaft or tool spindle C carrying the 70 chuck C'.

75 The casing of the tool is made in two parts A, A', attached together by means of screws a passing through the orifices a', and serving to hold a bushing a² for the shaft C. The driving member or operating spindle B' has a recess or channel b' in which the end of the shaft C works, which member may be partly inclosed by the hollow handle A³, and a side handle A⁴ is also provided 80 for purposes of convenience in-holding the instrument.

85 In the embodiments shown in Figs. 6 and 7, the parts are so designed that the axes of the gear wheels will lie at right angles to each other. In Fig. 6, the oppositely disposed gear wheels M and N contained in the casing A¹⁵ are driven by the gears l and l' of the shaft L, the gear N being 90 fixedly attached to the spindle B¹⁰, while in Fig. 7, the oppositely disposed gears K and K', inclosed in the casing A²⁰ are driven by the gears j and j' of the shaft J, the gear K being fixed to the spindle B¹⁰. The driving shaft of the device may be provided with a 95 friction coupling which can be made in one of a number of ways, preferably by making the coupling in two halves, one, the lower, part H' of which is shown in Fig. 7, one end of the coupling preferably extending 100 over the driving shaft, and the other end extending over the flexible shaft B. The said parts of the coupling are ordinarily made with grooves into which the shoulder h² of the driving shaft and the shoulder h⁴ of the 105 flexible shaft may respectively work. Upon the top part or cover of the coupling being placed over the lower part H', the two said parts of the coupling may be held together and tightened as desired by means of small 110 adjusting screws in the ordinary manner, or by means of tapered threads and nuts. The two parts of the coupling may be drawn together or tightened to any suitable 115 degree, depending upon the size of the drill or tap, so that when one or the other of the latter is subjected to too much strain, the coupling will slip either on the driving shaft, or on the flexible shaft, or both, and prevent the breakage of the tool. 120

125 Another form of the coupling is shown in Fig. 8, where the friction clutch H ordinarily has a solid portion h² to which are hinged, as at h³, two exteriorly threaded members h, the said thread being tapered, and the said members h lying a short distance apart, over which the clamp nut h' is forced and tightly held to the flexible shaft B, which latter has a shoulder located in the solid portion of the coupling in order to 130

prevent it from slipping off. At h^s the pin hole is made slightly oval to allow the members h to adapt themselves to the shaft B in case of wear or otherwise.

5 I wish it to be understood that I do not desire to be limited to the exact details of construction shown and described, for obvious modifications will occur to a person skilled in the art.

10 What I claim is:—

1. A portable drilling and tapping device adapted to be moved bodily about in operation and comprising a casing, a longitudinally movable rotatable tool spindle extending into the casing, two gear clutches in the casing arranged to be alternately operatively engaged by the spindle in different longitudinal positions of the spindle, speed and direction changing intermediate means 15 operatively connecting the two gear clutches, and two driving members, one driving member entering through the end of the casing and being directly connected to one gear clutch and the other driving member entering through the side of the casing and being directly connected to the intermediate means, whereby power may be directly applied to either the gear clutch or to the intermediate 25 means.

2. A portable drilling and tapping device adapted to be moved bodily about in operation and comprising a casing, a longitudinally movable rotatable tool spindle extending into the casing, two gear clutches in the 30 casing arranged to be alternately operatively engaged by the spindle in different longitudinal positions of the spindle, speed changing intermediate means operatively connecting the two gear clutches, two driving members, one driving member entering through the end of the casing and being directly connected to the intermediate 35 means.

40

nected to one gear clutch and the other driving member entering through the side of the casing and being directly connected to the intermediate means, whereby power may be directly applied to either the gear clutch or to the intermediate means, and a detachable hollow handle adapted to be secured to the casing concentrically of either driving member. 45

50

3. A portable drilling and tapping device adapted to be moved bodily about in operation and comprising a casing, a longitudinally movable rotatable tool spindle extending into the casing, two gear clutches in the 55 casing arranged to be alternately operatively engaged by the spindle in different longitudinal positions of the spindle, means for holding the spindle in locked relation in engagement with either of the two gear clutches, speed-changing intermediate means operatively connecting the two gear clutches, two driving members, one driving member entering through the end of the casing and being directly connected to one gear clutch 60 and the other driving member entering through the side of the casing and being directly connected to the intermediate means, whereby power may be directly applied to either the gear clutch or to the intermediate 65 means, and a detachable hollow handle adapted to be secured to the casing concentrically of either driving member. 70

75 In testimony of the foregoing specification, I do hereby sign the same in the city of New York, county and State of New York, this first day of September 1909.
